ELECTRONIC OSCILLATOR

Louis Malter, Collingswood, Jan A. Rajchman
and Robert Rhea Goodrich, 2nd, Camden,
N. J., assignors to Radio Corporation of Amer-
ica, a corporation of Delaware

Application March 28, 1936, Serial No. 71,360

5 Claims. (Cl. 250—36)

Our invention relates to electronic devices. More specifically, our invention deals with electronic tubes which depend upon the emission of secondary electrons.

5 We are aware of electronic devices in which a magnetic field, whose lines of force are substantially parallel to the cathode, is employed. Such devices are called magnetrons, and require a heated cathode as an electron emissive source. 10 One of the objects of the present invention is in means for establishing electronic oscillation without the uses of the heated cathode type of electron emitter.

Another object is to cause electronic oscillations to be established between a pair of concentric cylindrical electrodes one of which has an electron emissive surface. A further object is to create a push-pull type of electronic oscillator. A still further object is to restrict the electronic movements to a region between the electrodes and thereby prevent excessive movement of electrons which will not contribute to efficient operation.

Our invention may be best understood by reference to the accompanying drawings in which Figure I is a schematic diagram of one embodiment of our invention,

25 Figure II is a schematic diagram of an electronic oscillator embodying our invention and including electronic shields,

30 Figure III is a view illustrating a modification of Figure II,

Figure IV is a diagram of a push-pull oscillator embodying our invention,

35 Figure V is a view illustrating a modification of Figure IV, and

Figure VI is a diagrammatic view showing further modifications of my invention.

In describing the several figures similar reference numerals will be used to indicate similar elements. In Figure I within an evacuated envelope 1, a pair of concentrically arranged cylindrical electrodes 3, 5 are suitably mounted by supporting wires 7, 9. The inner cylinder 5 has 40 its outer surface treated with caesium on silver oxide or any other suitable material to make this electrode surface electron emissive. The ends of the outer or accelerating electrode preferably over-lap the inner or electron emissive electrode.

45 The accelerating electrode is maintained at a positive potential with respect to the emissive electrode by a polarizing battery 11. A tunable circuit 13 is serially connected between the electrodes as shown. The tunable circuit is composed of an inductor 15 and a variable capacitor

17. A solenoid 19, permanent magnet, or electromagnet is used to establish a magnetic field whose lines of force are substantially parallel to and coincident with the axis of the electrodes. If a solenoid 19 is used, as shown in section in 5 Figure I, battery 21 may be used as a source of energy.

The theory of the operation of our device is not entirely understood but it is believed that a small amount of residual gas within the envelope 10 or a photo-electric effect of light falling on the electron emissive surface may release electrons from the surface of the electron emissive element. These electrons start toward the positively charged accelerating anode at relatively high 15 velocity. The magnetic field causes these electrons to follow a curved path which extends outwardly from the inner electrode toward the anode and back toward the cathode. The electron movement, or some similar effect, starts transient 20 currents flowing in the resonant circuit 13. These currents establish potentials which attract the electrons toward the secondary emissive surface at relatively high velocities. The electrons moving at high velocities give up their energy upon 25 striking the electron emissive surface and thereby release a larger number of electrons. These electrons in turn start toward the accelerating electrode which has again become relatively positive and the cycle is repeated. At each repetition 30 of the cycle increasing numbers of electrons are emitted. The increasing electron emission and movement supports and sustains oscillations in the tunable circuit 13.

The embodiment of our invention illustrated in 35 Figure II is similar to Figure I with the addition of means to prevent the electrons from taking paths outside of the juxtaposed electrode surfaces. A pair of discs 23, 25 having a diameter intermediate the diameter of the accelerating 40 and emissive electrodes are positioned adjacent the ends of the emissive electrode by supporting leads 27, 29. The disc shape electrodes are connected to the battery 31. The positive terminal of this battery 31 is connected to the negative 45 terminal of biasing battery 11. The disc shape electrodes may be maintained at the same or different negative potentials. The negatively polarized discs will maintain the electron field within the proper boundaries for maximum efficiency. 50 These discs are preferably made of a material which does not impair the magnetic field.

In Figure III a modification of Figure II has been illustrated in which a pair of mica discs 33, 55 35 are substituted for the disc electrodes 23, 25.

The mica discs are self-biasing; i. e., electrons strike the disc and charge it negatively. The negatively charged discs repel electrons which might otherwise follow paths beyond the adjacent 5 surface of the accelerating and emissive electrodes.

In Figure IV, a schematic representation illustrates an embodiment of our invention applied to a push-pull oscillator. Within an evacuated envelope 41 a cylindrical accelerating anode 43 is supported by suitable wires 45. A pair of cylindrical electrodes 47, 49 are concentrically mounted within the accelerating anode by supporting wires 51, 53. The outer surfaces of these 10 electrodes 47, 49 are treated to render them highly secondary emissive. The leads 51, 53 from the electrodes 47, 49 are respectively connected to the opposite terminals of a tunable circuit 55 which is composed of an inductor 57 and a capacitor 59. 15 A polarizing battery 61 is connected between the accelerating anode 43 and the mid-point 63 on the inductor 57. The positive terminal of the battery is connected to the anode. The magnetic field has been represented as a magnetic core 67 20 which is energized by current from battery 69 flowing in the solenoid winding 71. It should be understood that a solenoid type winding may be used in place of the electromagnet shown. Disc shape electrodes 23, 25 may be placed adjacent 25 the ends of the cylindrical electrode 47. Likewise disc shape electrodes 23, 25 may be located adjacent the ends of the cylindrical electrode 49. The disc shape electrodes 23, 25 are biased negatively by suitable connections to negative terminals 30 of a battery 31. The positive terminal of the biasing battery 31 is connected to the positive terminal of the polarizing battery 61.

In Figure V the essential elements are similar to the elements of Figure IV. In the instant 40 arrangement the electrode arrangement is reversed. The inner electrode 81 is made with an electron emissive surface, and the pair of outer electrodes 83, 85 act as accelerating anodes. The accelerating anodes 83, 85 are connected to the 45 terminals of the tuned circuit 55. The inner electrode 81 is connected to the negative terminal of the battery 61 whose positive is connected to the mid-point 63 of inductor 57. The magnetic field may be due to an electromagnet, permanent 50 magnet or solenoid.

The theory of operation of each of the push-pull oscillators is essentially the same as the single electronic oscillators described above. Inasmuch as push-pull operation is well known to those skilled in the art, a detailed description is unnecessary. It should be understood that various features of the several embodiments of our invention may be combined. By way of example, the accelerating and emissive electrodes of Figures 55 I, II or III may be interchanged, accompanied, of course, by a proper phasing of the biasing battery. Likewise, the disc or shielding electrodes of Figures II or III may be employed with the arrangement shown in Figure V, as for example 60 illustrated in Figure VI.

65 Referring to Figure VI, within an envelope 100 are arranged a pair of inner cylindrical electrodes 101, 103. The outer surfaces of these electrodes are treated to make them secondarily emissive. Adjacent the ends of the inner electrodes are

positioned self-biasing mica discs 105. Anode electrodes 107, 109 are respectively concentrically mounted with respect to the inner electrodes 101, 103. The anode electrodes 107, 109 are respectively connected to the terminals of a tuned 5 circuit 111. The inner electrodes 101, 103 are connected together and to the negative terminal of a polarizing battery 113. The positive terminal of the battery 113 is connected to a point intermediate the terminals of the tuned circuit 111. 10 The operation of this circuit is substantially equivalent to the operation of the circuits previously described.

We claim as our invention:

1. An electron oscillator comprising an evacuated envelope, a hollow cylindrical electrode mounted within said envelope, a pair of cylindrical electrodes of substantially the same diameter spaced apart and coaxially mounted within the first mentioned electrode, said pair of electrodes having surfaces adapted to emit secondary electrons upon impact of primary electrons, a tuned circuit, connections from one of the terminals of said tuned circuit to one of said pair of electrodes and from the other terminal to the other electrode of said pair, a source of polarizing potential connected between the outer electrode of said concentrically mounted electrodes and said tuned circuit, and a magnetic field whose lines of force are substantially coaxial with respect to said concentrically mounted cylinders. 15

2. An electron oscillator comprising an evacuated envelope, a cylindrical electrode mounted within said envelope, said electrode having a surface adapted to emit electrons upon electron impact, a pair of hollow accelerating anodes spaced apart and concentrically mounted with respect to said first mentioned electrode, a tunable circuit, connections from said tunable circuit to said pairs of electrodes, a source of biasing potential 20 connected between said first-mentioned electrode and said tunable circuit, and a magnetic field whose lines of force are substantially coaxially arranged with respect to said concentrically mounted electrodes. 35

3. A device of the character of claim 1 including means for maintaining the electronic movements within the juxtaposed electrode surfaces. 40

4. A device of the character of claim 2 including means for maintaining the electronic movements within the juxtaposed electrode surfaces. 50

5. An electron oscillator comprising an evacuated envelope, a cylindrical electrode mounted 55 within said envelope, a pair of electrodes spaced apart and concentrically mounted with respect to said first mentioned electrode, at least one of said pair of electrodes having a surface of secondarily emissive electron material, a tunable circuit, push-pull circuit connections between said tunable circuit and said electrodes, means for polarizing said first mentioned cylindrical electrode positively 60 with respect to said emissive electrode or electrodes, and means for establishing a magnetic field whose lines of force are substantially coaxial with respect to said cylindrical electrode. 65
